UNITED STATES PATENT OFFICE

162,134

STOCKING

George Dewey Dowell, Winston-Salem, N. C., assignor to Hanes Hosiery Mills Company, Winston-Salem, N. C., a corporation of North Carolina

Application May 20, 1950, Serial No. 10,055

Term of patent 14 years

(Cl. D47—7)

To all whom it may concern:

Be it known that I, George Dewey Dowell, a citizen of the United States, residing at 501 Irving Street, Winston-Salem, State of North Carolina, have invented a new, original, and ornamental Design for a Stocking, of which the following is a specification, reference being had to the accompanying drawing, forming a part hereof.

Fig. 1 of the drawing is a view in side elevation of the stocking; Fig. 2 is a fragmentary showing of the stocking shown in Fig. 1, showing in greater detail the design in the heel portion thereof. It is to be understood that the ornamentation shown in the drawing similarly occurs on the opposite side of the stocking.

I claim:

The ornamental design for a stocking, as shown and described.

GEORGE DEWEY DOWELL.
